UNITED STATES PATENT OFFICE.

HAROLD S. LOOMIS, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RELAY.

1,286,364.

Specification of Letters Patent.

Patented Dec. 3, 1918.

Application filed July 23, 1917. Serial No. 182,156.

To all whom it may concern:

Be it known that I, HAROLD S. LOOMIS, a citizen of the United States, residing at Wilkinsburg, in the county of Allegheny and State of Pennsylvania, have invented certain new and useful Improvements in Relays, of which the following is a specification.

My invention relates to relays, and particularly to relays adapted for use in railway signaling.

I will describe one form of relay embodying my invention and will then point out the novel features thereof in claims.

15. The accompanying drawing is a view showing diagrammatically one form of relay embodying my invention and also showing one manner of employing the relay to control a light signal.

20. Referring to the drawing, my improved form of relay is designated generally at L, and as here shown, comprises a pivotally mounted main shaft M, which may be rocked by any suitable means. As here shown, this 25 shaft carries a vane V of electro-conductive material which coacts with suitable means such as shown in Letters Patent No. 838,404, granted M. R. Hanna, whereby the shaft may be rocked in either direction. Located 30 above the shaft M is a countershaft M' for controlling contact fingers g and y, coöperating respectively with fixed contact blocks g' and y'. This countershaft M' is operatively connected to the main shaft M for

35 movement therewith, by means of a link 15 and arms 16 and 17 formed on the shafts M and M' respectively, such link connecting said arms in the manner shown. M² is a second counter shaft for controlling a contact finger r which coöperates with a fixed contact block r', such shaft being operatively connected to the main shaft by means of a pair of links 18 and 19. The upper ends of the links are pivotally connected to an

40 arm 20 carried by the countershaft M², while the lower ends of the links are formed with slots 18^a and 19^a respectively, for slidably receiving pins 21 and 22 formed on the opposite ends of a bar 23. This bar 23 is fixed 45 at its medial portion to the main shaft M for rocking movement therewith.

As shown in the drawing, the vane V is biased to an intermediate position by virtue of the combined weights of the pawl 24 and bar 20 being equally distributed upon

opposite sides of the shaft M by means of the links 18 and 19. With vane V in the intermediate position contacts g—g' and y—y' are open, while contact r—r' is closed, as shown in the drawing. When the vane V is moved downwardly from the intermediate position to the position indicated in dot-and-dash lines, main shaft M is rocked in clockwise direction, thereby elevating arm 16, link 15, and arm 17 to swing countershaft M' in clockwise direction, thus closing contact y—y'. With this downward movement of vane V, the left-hand end of bar 23 is lifted, thus causing pin 21 to engage the upper end of slot 18^a and lift link 18. Arm 20 is thus raised, causing partial rotation of countershaft M² in a clockwise direction to open contact r—r'. When the vane V is moved upwardly from the intermediate position to the position indicated in dash lines, shaft M is rocked in counter-clockwise direction, whereby arm 16 is swung downwardly to partially rotate countershaft M' in counter-clockwise direction, thereby closing contact g—g. During upward movement of vane V the right-hand end of bar 23 is raised, thus causing pin 22 to lift link 19 and thereby open contact r—r', as when the vane was moved to its lower position. By reason of the pin 85 and slot connections between bar 23 and the links 18 and 19, movement of either link by its pin is not restricted by the other link and pin.

From the foregoing it will be evident that, 90 with only the apparatus as thus far described, when vane V is moved from the upper extreme position to the lower extreme position or vice versa to reverse contacts g—g' and y—y', contact r—r' would be 95 momentarily closed. This momentary closure of contact r—r' is undesirable in some instances, as for example, when the relay is employed to control a light signal. In order to maintain contact r—r open during 100 such reversal of the contacts, I provide a retarding device F, which, as here shown, comprises a pawl 24, pivoted to the free end of the arm 20, and which is adapted to coact with a ratchet wheel W fixed to a shaft M³. 105 Also fixed to the shaft M³ is a solid wheel D having considerable inertia.

The operation of the retarding device F taken in conjunction with the relay is as follows: Assume that vane V has been 110

moved to the lower position so that contact $y-y'$ is closed and contacts $r-r'$ and $g-g'$ are open. Such movement of the vane elevates arm 20 as has been described, thus causing pawl 24 to be lifted into active engagement with the ratchet wheel W so that the pawl will drive the ratchet wheel when arm 20 again descends. Now assume that the vane is moved continuously from the lower position to the upper position to cause a reversal of contacts $g-g'$ and $y-y'$. During this reversal, shaft M² attempts to return to its normal position wherein contact $r-r'$ is closed, but in so doing it must rotate wheel D. The inertia of this wheel is such that during the reversal of the vane, shaft M² does not return far enough to close contact $r-r'$, and, consequently, a momentary closure of this contact is prevented. In the same manner, momentary closure of contact $r-r'$ is prevented when the vane moves continuously from its upper to its lower extreme position.

In the present instance I have shown relay L controlling a light signal S, which signal comprises three electric lamps designated G, Y and R. The beams from these lamps are colored green, yellow and red respectively, to indicate "proceed", "caution" and "stop" respectively, as is well understood in the art of railway signaling. Lamp G is connected in a circuit which includes contact $g-g'$, this circuit being from battery B through wires 25 and 26, contact finger g , contact block g' , wire 27, lamp G and common return wire 0 back to battery. Lamp Y is connected in a circuit which includes contact $y-y'$, this circuit being from battery B through wire 25, contact finger y , contact block y' , wire 28, lamp Y, wire 29, and common return wire 0 to battery. Lamp R is connected in a circuit which includes contact $r-r'$, this circuit being from battery B through wires 25 and 30, contact finger r , contact block r' , wire 31, lamp R, wire 32, and common return wire 0 back to battery.

It will be evident from this arrangement of circuits that when the vane is in the intermediate position lamp R is illuminated while lamps G and Y are extinguished, and that when the vane occupies the lower position lamp Y is illuminated and lamp R is extinguished. Similarly, when the vane occupies the upper position lamp R is extinguished and lamp G is illuminated. However, when the vane is moved from the lower to the upper position, or vice versa, to extinguish lamp Y and illuminate lamp G or vice versa, lamp R remains extinguished by virtue of the fact that the retarding device F prevents closing of contact $r-r'$ during such change, as has been described.

From the foregoing it will be manifest that I have provided a relay for actuating

a light signal in such manner as to prevent momentary illumination of the "stop" lamp when changing the indication of the signal from "caution" to "proceed", or vice versa.

Although I have herein shown and described only one form of relay embodying my invention, it is understood that various changes and modifications may be made therein within the scope of the appended claims without departing from the spirit and scope of my invention.

Having thus described my invention, what I claim is:

1. A relay comprising an operating member movable in opposite directions from an intermediate position to two extreme positions, a contact biased to the closed position but opened by said operating member when the member moves in either direction from said intermediate position, and inertia controlled means for preventing closure of said contact when said operating member moves continuously from one extreme position to the other.

2. A relay comprising an operating member movable in opposite directions from an intermediate position to two extreme positions, a contact biased to one position but movable to another position when said operating member moves in either direction from said intermediate position, a rotatable device, and means operatively connected with said contact for causing rotation of said device when the contact is moving in response to its bias but not when the contact is being moved in opposition to its bias by said operating member, said rotatable device having sufficient inertia to prevent movement of said contact to the position toward which it is biased when said operating member moves continuously from one extreme position to the other.

3. A relay comprising a main shaft movable in opposite directions from an intermediate position to two extreme positions, a countershaft biased to turn in one direction, means interposed between said two shafts for turning the countershaft in opposition to its bias when the main shaft moves in either direction from its intermediate position, means for retarding the return of said countershaft in response to its bias while the main shaft is moving from one extreme position to the other, and a contact controlled by said countershaft.

4. A relay comprising a main shaft movable in opposite directions from an intermediate position to two extreme positions, a countershaft biased to turn in one direction, means interposed between said two shafts for turning the countershaft in opposition to its bias when the main shaft moves in either direction from its intermediate position, and for exerting a force on the main shaft tending to return it to the intermediate position,

due to the bias of the countershaft, means
for retarding the return of said countershaft
in response to its bias while the main shaft
is moving from one extreme position to the
5 other, and a contact controlled by said
countershaft.

5. A relay comprising a main shaft movable
in opposite directions from an intermediate
position to two extreme positions,
10 two contacts one or the other which is closed
according as said shaft occupies one extreme
position or the other, a countershaft biased
to turn in one direction, means interposed
between said two shafts for turning the
15 countershaft in opposition to its bias when
the main shaft moves in either direction
from its intermediate position, means for
retarding the return of said countershaft in
response to its bias, and a contact controlled
20 by said countershaft.

6. A relay comprising a main shaft mov-

able in opposite directions from an intermediate position to two extreme positions, a countershaft biased to turn in one direction, means interposed between said two shafts 25 for turning the countershaft in opposition to its bias when the main shaft moves in either direction from its intermediate position, means for retarding the return of said countershaft in response to its bias while the 30 main shaft is moving from one extreme position to the other, and a contact controlled by said countershaft and closed only when said countershaft occupies the position toward which it is biased. 35

In testimony whereof I affix my signature
in presence of two witnesses.

HAROLD S. LOOMIS.
